UNITED STATES PATENT OFFICE.

RUDOLPH HÖRMANN, OF HOBOKEN, NEW JERSEY.

BUTTON.

SPECIFICATION forming part of Letters Patent No. 531,940, dated January 1, 1895.

Application filed December 16, 1891. Serial No. 415,809. (No model.)

To all whom it may concern:

Be it known that I, RUDOLPH HÖRMANN, of Hoboken, Hudson county, and State of New Jersey, have invented a certain new and useful Improvement in Buttons, of which the following is a specification.

This invention relates more particularly to trousers' buttons and it consists of the construction and novel arrangement of parts as hereinafter set forth.

The object of my improvement is to provide a trousers button in which a low grade or cheap metal may be employed, but which when completed, will be strong and serviceable, and a further object is to provide a button in which two or more colors or designs may be presented to view.

In the accompanying drawings Figure 1 is a front view of a button embodying my improvement. Fig. 2 is a back view. Fig. 3 is a section.

Referring by letter to the drawings, A designates the back plate of the usual concavo-convex form.

25 A' is an intermediate plate depressed or concaved at its central portion as shown and having the annular outwardly extending bead or rim a. The plate A' is somewhat smaller in circumference than the plate A, and eyes 30 a' are punched through both these plates as shown.

B designates an outer annular plate having its inner edge turned inward, as at b, and impinges against the surface of the plate A'.

35 The outer edge of the plate B is turned in-

ward, at substantially right angles to the surface of the plate, and then outward forming the annular rim or channel b'.

It will be seen that the annular plate B closely embraces the bead or rim a of the 40 plate A' and the plate A' is, therefore, held in position by the plate B.

B' is an annular rim embracing the edges of the plates A, B, and serving to lock the several parts firmly together. It will be seen 45 that this button consists of four parts, the back plate A, the intermediate plate A', the annular plate B and the locking rim B'.

By employing different metals for the parts A', B, B', or by japanning a part or all of the 50 plates in different colors, or by providing the plate B with designs, etched or otherwise, the button will present a very ornamental appearance.

Having described my invention, what I 55 claim is—

In a button the combination of the back plate, the intermediate plate having the annular bead or rim a, the annular plate B having the inwardly turned edge b, and the outer 60 edge turned inward forming the flange or channel b', and the locking rim B', substantially as specified.

In testimony whereof I have signed my name to this specification in the presence of 65 two subscribing witnesses.

RUDOLPH HÖRMANN.
